UNITED STATES PATENT OFFICE.

JOHN W. FOWLER, OF BROOKLYN, NEW YORK.

STOVE-DOOR.

SPECIFICATION forming part of Letters Patent No. 366,088, dated July 5, 1887.

Application filed September 27, 1886. Serial No. 214,609. (No model.)

To all whom it may concern:

Be it known that I, JOHN W. FOWLER, a citizen of the United States, and a resident of Brooklyn, in the State of New York, have invented a new and useful Improvement in Stove-Doors, of which the following is a specification.

This invention relates to that class of stove-doors in which the doors proper slide in horizontal ways.

It consists, generally speaking, in an improved "stove-door" of this class which is primarily designed for upright ear-stoves, but may be used on stoves or furnaces of almost any description.

The objects of this invention are, first, to adapt a sliding stove-door and its appurtenances to serve as a "ventilating-register" without additional parts; secondly, to adapt such a door to so operate without supplemental openings in the stove; thirdly, to adapt such a door, so operating, to be securely fastened in its ventilating position; fourthly, to adapt it to be securely fastened in each of its three positions by a simple fastening device; fifthly, to adapt it to be so fastened by a gravitating bolt; and, sixthly, to adapt the door proper to be made with a projecting face and hollow back without interfering with its operation as a ventilating-register, as aforesaid.

Two sheets of drawings accompany this specification as part thereof.

Figure 1 of these drawings represents a front view of a cylindrical stove provided with my improved stove-door. Fig. 2 represents a vertical section on the line 2 2, Fig. 1. Fig. 3 represents a horizontal section on the line 3 3, Fig. 1. Fig. 4 represents a vertical section through the door proper on the line 4 4, Fig. 3. Fig. 5 represents a top view of the door proper. Fig. 6 represents, on a smaller scale, a series of horizontal sections through the door and stove-front, showing the door proper in its several positions of rest. Fig. 7 represents a front view of a stove provided with a ventilating stove-door, illustrating a modification of the same invention. Fig. 8 represents a horizontal section on the line 8 8, Fig. 7; and Fig. 9 represents a series of horizontal sections in the form of diagrams, show-

ing the door proper in its several positions of rest.

Like letters of reference indicate corresponding parts in the several figures.

In applying my invention to a stove or furnace, A, I attach thereto a pair of horizontal guide-rails, B C, which are made to support a door proper, D, (to which the term "door" hereinafter refers,) said rails being located immediately above and immediately below the doorway E, which may be surrounded by a thin door-frame, F, having a corresponding opening, as shown; but this as a distinct part is not considered essential. It forms part of what may be termed the "front" of the stove, 55 which must simply be adapted to a sliding door. To the front of the stove the rails B C and door D are conformed, being in the examples segments of circular rings, and the extended door or the front of the stove is provided 60 at one of the vertical edges of the former with ventilating-openings V, which are consequently unmasked or masked by the movements of the door itself, without supplemental parts. In the example represented by Figs. 1 to 6, inclusive, said ventilating-openings are formed 65 in the door D, and communicate with said doorway-opening E itself when unmasked, as seen in the second diagram in Fig. 6, so as to obviate forming supplemental openings in the 70 stove. In the modification illustrated by Figs. 7 to 9 the ventilating-openings V are formed 75 in the stove-front, and the lateral extension of the door D is imperforate. In both examples provision is made for fastening the door D in 80 a position of rest intermediate between closed and open, to unmask the ventilating-openings without otherwise opening the stove. The same fastening device, G, coacts with three detents, H I J, in the respective positions of rest 85 of the door indicated in Figs. 6 and 9, and said fastening device is, by preference, a gravitating bolt provided with a lifting-knob, K, said detents being formed by lugs on the lower guide-rail, C. Said bolt G, as shown, is superposed on the outer surface of the door and is guided by slots L, Fig. 4, occupied by studs on the bolt, into which a pair of screws are driven, one of these screws serving to attach the knob K. Said detents H I J are formed in the shape 90 of the letter "U".

of notches by lugs on the outer edge of said guide-rail C. Both guide-rails are attached to the stove, together with said doorway-frame F, by bolts M, and the door is constructed with 5 lugs N, Figs. 2 and 5, on its upper and lower edges to coact with guide-grooves formed by the rails B and C, respectively; but these and like details of mechanical construction form no part of my present invention. The door D, 10 Figs. 1 to 6, is, moreover, constructed with a recessed back, so that its face may project flush with the outer edges of the guide-rails, or as may be desired, without rendering it unduly heavy and to facilitate fitting or conforming it 15 to the stove-front. It has close edges, as clearly shown in the several sectional views, and is provided additionally with vertical partition-ribs O P, which coact with the stove-front in the closed and ventilated positions of the door 20 to resist the entrance of air at the edges of the doorway. Said rib O is of especial importance in connection with ventilating-openings in the recessed door itself to resist the entrance of air through the door and doorway 25 when the door is "closed." (See Fig. 6.) In the modification, Figs. 7 to 9, there is no need for this rib, but the door is provided with a rib, P, similar to the one so marked in Figs. 1 to 6.

30 Having thus described my said improvement in stove-doors, I claim as my invention and desire to patent under this specification—

1. The combination, substantially as herein specified, of the front of a stove or furnace and a horizontally-sliding door of greater lateral extent than the doorway-opening in said front, one of the parts being provided with ventilating-openings which are masked and unmasked by sliding the door itself.
2. The combination of the front of a stove or furnace and a horizontally-sliding door of greater lateral extent than the doorway-opening in said front, and provided with ventilating-openings which are unmasked by bring-

ing them opposite said doorway-opening by 45 sliding the door, substantially as herein specified.

3. The combination of the front of a stove or furnace, a horizontally-sliding door of greater lateral extent than the doorway-opening in said front, and means for fastening said door in a position intermediate between closed and open, substantially as herein specified, ventilating-openings in one of the parts being unmasked in said position of the door. 50

4. The combination, substantially as herein specified, of the front of a stove or furnace, a horizontally-sliding ventilating-door of greater lateral extent than the doorway-opening in said front, and provided with a suitable fastening device, and a guide-rail attached to said front and provided with detents which coact with said fastening device when the door is closed, ventilated, and open, respectively. 55

5. The combination of the front of a stove or furnace, a horizontally-sliding ventilating-door of greater lateral extent than the doorway-opening in said front, and provided with a gravitating bolt, and a guide-rail attached to said front, coacting with the lower edge of 60 said door and provided with detents which coact with said bolt in the respective positions of rest of the door, substantially as herein specified. 65

6. In combination with the front of a stove or furnace provided with a suitable doorway-opening, a horizontally-sliding door of greater lateral extent than said doorway-opening, and having a recessed back divided vertically by a partition-rib, and ventilating-openings on 70 one side of said rib, which are unmasked by bringing them opposite said doorway-opening by sliding the door, substantially as herein specified. 75
